UNITED STATES PATENT OFFICE.

CHESTER K. HANN, OF COLUMBUS, OHIO.

GRASS-CATCHER.

No. 824,717.

Specification of Letters Patent.

Patented July 3, 1906.

Application filed September 16, 1905. Serial No. 278,732.

To all whom it may concern:

Be it known that I, CHESTER K. HANN, a citizen of the United States, residing at Columbus, in the county of Franklin and State 5 of Ohio, have invented certain new and useful Improvements in Grass-Catchers, of which the following is a specification.

My invention relates to new and useful improvements in grass-catchers.

The object of the invention is to provide a simple catcher of superior construction comprising a fabric body, a foldable frame, and a spring-attaching frame acting to hold the bottom of the body in shape.

Another feature resides in the provision of a spring without stiffening-rods and guides for the engaging members of the attaching-frame, as well as reinforcing means for the front edge of the bottom.

Finally, the object of the invention is to provide a device of the character described that will be strong, durable, efficient, and simple and inexpensive to make.

With the above and other objects in view the invention consists of the novel details of construction and operation a preferable embodiment of which is described in the specification and illustrated in the accompanying drawings, wherein—

Figure 1 is a side elevation of the catcher, a portion of the body being broken away to illustrate the hinge-joint. Fig. 2 is a plan view of the same. Fig. 3 is a front elevation, and Fig. 4 is a partial vertical sectional view taken on the line $x-x$ of Fig. 2 and greatly enlarged.

In the drawings, the numeral 1 designates the fabric body of the catcher, which has the usual shape and is provided with a fabric bottom 2. Along its upper edge, which inclines upwardly and rearwardly, the body is engaged about a substantially U-shaped top frame 3. The top frame is formed with eyes 4 at its forward ends which engage loosely in the double coils 5 of an inverted substantially U-shaped front frame 6, thus forming hinge-joints. The front frame has its vertical ends extending downwardly at an angle to the top frame and is formed at its lower ends with eyes 7. The eyes 7 engage in eyes 8 of an upper transverse rod 9, extending across the bottom 2 at its front edge. Beneath the rod 9 a lower transverse rod 10, separated therefrom, extends across the bottom and is formed with eyes 11, bent at right angles and coiled about the upper rod 9.

The eyes impinge the inner sides of the eyes 8 of the front frame, thus securing the lower rod against longitudinal movement on the upper rod 9.

An attaching-frame 12, secured to the body along the intersection of its bottom 2 and its rear end wall, serves to hold the lower portion of the body in shape. The frame 12 is provided with forwardly-extending portions converging toward each other and looped to form eyes 14, adjacent to and in the rear of the rods 9 and 10. These eyes are engaged by the free ends of a coiled spring 15, while engaging members or hooks 16 extend forwardly from the eyes, passing between the upper and lower rods 9 and 10, which form guides therefor. The members 16 are thus resiliently connected and spring apart against the tension of the coiled spring 15, thereby being firmly held in contact with the lawnmower with which they are engaged.

It will be noted that the bottom fabric 2 is passed about the lower rod 10 and carried back upon itself, as indicated at 2^a in Fig. 4, while a casing-strip of fabric 17 is placed along the under side of the bottom, carried about and over the rods 9 and 10, and passed down and beneath the coiled spring 15 onto the portion 2^a of the bottom. The rearwardly-extending portions of the casing-strip 17 and the portion 2^a are suitably stitched to the bottom 2 transversely, thereby being held in place and securing the rods against displacement. The casing-strip 17 and the portion 2^a, while acting more especially to hold the rods 9 and 10 in place, also reinforce the front edge of the fabric bottom 2. By observing Fig. 3 it will be noted that the casing-strip 17 extends only between the engaging members 16 of the attaching-frame 12, the rods 9 and 10 on each side of the strip being exposed and providing guides or openings in which the said engaging members have free play. In constructing the top frame 3, the front frame 6, the rods 9 and 10, and the attaching-frame 12 any suitable wire having a certain amount of resiliency and rigidity may be employed. The wire should be stiff enough to brace and hold the body in shape.

By provision of the hinge-joints formed between the parts by the various eyes the catcher may be readily folded down flat to facilitate transporting and shipping. The catcher is readily folded by swinging the front frame 6 downward and forward, the

top frame thereby being swung downward and forward and the parts thus lying comparatively flat. Much stress is laid on the front frame 6, which greatly strengthens the 5 front portion of the catcher and prevents the sides from bulging outwardly or spreading.

Having now fully described my invention, what I claim, and desire to secure by Letters Patent, is—

- 10 1. In a grass-catcher, a body, jointed stiffening-frames for the body, separated guide-rods extending across the front of the body, attaching members passing between the rods, and resilient means for connecting the said members.
- 15 2. In a grass-catcher, a body, jointed stiffening-frames for the body, separated guide-rods extending across the front of the body, attaching members passing between the rods, 20 resilient means for connecting the said members, and means for holding the rods together and the attaching members apart.
- 25 3. In a grass-catcher, a fabric body, a top frame attached to the upper portion of the top of the body and formed at its forward ends with eyes, a front frame having openings engaged by the eyes of the top frame to form hinge-joints, said front frame being provided

with eyes at its lower ends, a rod extending across the bottom of the body and formed 30 with eyes engaging with the eyes of the front frame to form hinge-joints, a second rod having a portion of its length separated from the first rod but having connection therewith, a spring-attaching frame carried by the bottom 35 of the body and acting to hold the lower portion of the body in shape, engaging members provided on the attaching-frame and extending between the rods, and a coiled spring having engagement with the attaching-frame.

4. In a grass-catcher, a body, a spring-attaching frame carried by the body, separated guide-rods between which the attaching-frame extends arranged along the front edge 45 of the bottom of the body, a portion of the bottom being carried about one of the rods to hold it in place, and a casing-strip carried about both rods and secured to the bottom with the said portion thereof.

In testimony whereof I affix my signature in presence of two witnesses.

CHESTER K. HANN.
